SPRAYING MACHINE

Miles H. Tuft, Huntington Park, Calif., assignor to Hardie Manufacturing Company, Hudson, Mich., a corporation of Michigan

Application December 28, 1953, Serial No. 400,481

4 Claims. (Cl. 299—29)

This invention relates to machines for spraying trees and crops with insecticides and similar materials, and more particularly relates to that type of spraying machine in which the liquid carrying the insecticide is carried and comminuted into a fine spray by a blast of carrier air.

It is an object of this invention to provide a machine having an air blast of great force and volume, whereby spray may be carried to great heights and distances from a machine of the ordinary truck or trailer type without use of booms or towers.

A further object of this invention is to provide a very compact spraying machine of the opposed dual-fan type, machines of this type having hitherto been so elongated as to be maneuverable only with difficulty in fruit orchards.

Another object of this invention is to provide a dual-fan type of spraying machine which delivers an air-blast concentrated into a radial zone of very little thickness, so that the need of dual liquid injector systems is obviated and the velocity of the blast is enhanced.

Still another object of my invention is to provide a spraying machine in which the air-blast, although developed by dual fans and of consequent large volume, is so delivered in what amounts to a single plane that very simple directional controls may be applied to the blast.

In general terms, I accomplish the foregoing objects and other advantages and improvements which will become apparent as the following specification proceeds, by disposing two fans in opposite ends of a very short cylindrical housing, the length of the housing cylinder being only great enough to provide a single row of peripheral orifices in the upper side wall of the cylinder for egress of air drawn by the fans into the cylinder. The air-blasts from the two opposed fans meet within the casing but in a manner hereinafter described in detail not repellent to either of them and emerge through the peripheral orifices as a unified blast of great force and volume. Hitherto it has been attempted to utilize two fans on spraying machines in order to obtain the double volume of air which would seemingly result by the logic of simple arithmetic. However it has always been found that one blast repelled the other, that efficient air-flow was destroyed by resultant turbulence, and that the net result was often less than the effect of a single fan, unless the two blasts were guided separately to their point of emergence, which necessitated a machine of enlarged and complex structure. In my invention, instead of a zone of conflict and opposition or an alternative structure of complex wind-tunnels, what may be termed a neutral zone is created at the center of the housing from which air-blasts aligned with the axes of the fans are excluded; air entering the housing adjacent to the peripheral exit orifices is allowed and assisted to take the shortest paths to the orifices; and air entering the housing at points more distant from the exit orifices and particularly at points across the central neutral zone from the orifices is guided into the neutral zone in a direction toward the orifices, whereby it sets up a unified directional flow, instead of turbulence, at the center of the housing and adds its volume, force and directional influence to those of the "short-path" air currents previously mentioned.

In the accompanying drawings, illustrative of a presently preferred embodiment of my invention,

2

Fig. 1 is a side elevational view of a spraying machine embodying my invention, showing how the blower of the machine may be closely coupled to a storage tank and pumping engine in a vehicle of moderate length.

Fig. 2 is an enlarged transverse vertical sectional view on the line 2—2 of Fig. 1, showing the system of movable baffles which provide directional control in the peripheral outlets;

Fig. 3 is a longitudinal vertical sectional view on the line 3—3 of Fig. 2, and on the same scale, illustrating the positions of opposed fans in relation to the central cowled zone and the outlets, and the means for directing air-flow across the central zone toward the outlets; and

Fig. 4 is a transverse horizontal sectional view on the line 4—4 of Fig. 2, showing in plan a preferred arrangement of said air-flow directing means.

Having reference now to the details of the drawings, there is shown in Fig. 1 a vehicle of trailer type mounted on wheels 6 and having a storage tank 7 for liquid insecticides carried centrally above the wheels. Forwardly of the wheels is a pumping engine, indicated by its ventilated cowling 8 and a platform 9 on which an operator may stand. A draw-bar, not shown, may extend from the platform 9, for connection to a tractor. The blower 10, in which the concepts of the present invention are embodied, is mounted at the rear of the vehicle. A shaft 11 extends rearwardly from the engine through the tank 7 and axially through the blower 10 where it supports for rotation the dual fans of the blower. The shaft 11 is also preferably connected by a chain 12 to a pump 13 which through conduits 14 supplies liquid to a nozzle ring 15. It will be understood that the shaft 11 is also available for driving stirring devices, not shown, within the tank 7. Control devices 16 may be made available close to the operator's station, with suitable leads 17 to the engine and to valves, not shown, on intake lines to the pump 13.

The blower 10 has a casing 20 in which two oppositely opening funnel-shaped members 21 and 22 are joined to end walls 23 and 24 which are spaced apart at their central portions to define a chamber 25 of generally cylindrical shape which may be quite short in length in comparison to its diameter. For considerably more than half their peripheries the end walls 23 and 24 converge 45 beyond the chamber 25, leaving between them a circumferential opening 26. In this portion of their peripheries the end walls 23 and 24 are held spaced by bolts 27 and have mounted between them a plurality of valve plates 28, hinged on bolts 29, as described in my copending application Serial No. 2,422,510, filed August 18, 1951, now Patent No. 2,670,566, in connection with a dust blower. By loosening and then tightening the bolts 27, the valve plates 28 may be secured by the pressure of the slightly flexible end walls 23 and 24 in adjusted positions in which 55 they divide the circumferential opening 26 into a plurality of outlet orifices 30 and control the direction of the air blasts issuing therefrom. In the remaining portion of their peripheries, which in a blower of this type will preferably be the bottom portion, the end walls 23 and 60 24 are joined by a side wall 31.

The shaft 11 extends through the center of the chamber 25 and has secured to it two fan-type impellers 32 and 33 mounted at opposite ends of the chamber 25 and in 65 opposed operational relationship so as to blow opposed blasts toward the central diametrical plane of the chamber 25. The impellers 32 and 33 preferably have central disks 34 to which blades 35 are diagonally secured, only the blade portions extending radially beyond the disks 34 being effective to propel air into the chamber 25. Secured 70 respectively to the funnel members 21 and 22 by suitable braces 36 are cowlings 37 and 38, each provided with

bearings 39 supporting the shaft 11. The cowlings 37 and 38 are substantially coextensive with the disks 34. The braces 36 may be straps or rods of small magnitude and offering little resistance to air-flow, so that the spaces between the cowlings 37 and 38 and the funnels 21 and 22 are substantially unimpeded annular inlet orifices 40 and 41, juxtaposed annularly to the blades 35 of the respective impellers 32 and 33, and admitting to the chamber 25 through said blades. Obviously the disks 34 also serve to define the annular orifices 40 and 41 and to screen the central portion of the chamber 25 from direct entry of air; the cowlings 37 and 38, by their outwardly convex shape, have the added function of assisting the funnels 21 and 22 in streamlining the flow of a large volume of air into the inlet orifice.

Extending inwardly of the chamber 25 from the side wall 31 in the central diametric plane of the chamber is a baffle plate 44. The plate 44 extends to about the level of the edges of the disks 34, so as to form a barrier between segments of the annular inlet orifices 40 and 41 adjacent the wall 31. A plurality of plates 45 are secured to the plate 44 at right angles thereto and extend inwardly of the chamber 25 substantially coextensively with the plate 44. The plates are preferably slightly inclined from the wall 31 in the direction of rotation of the impellers 32 and 33. Their number and spacing will depend upon the proportions of the segments of the orifices 40 and 41 between which the plate 44 imposes a barrier to the remainder of those orifices. The function of the plate 44 is to prevent opposed air blasts entering that portion of the chamber 25 from meeting and causing fluctuating turbulence, and the combined function of the plate 44 and plates 45 is to deflect the so-baffled air blasts to and across the relatively dead space between the disks 34 towards the outlet orifices 30. The length of the baffled segments of the inlet orifices 40 and 41 will depend upon the proportion of the periphery of the casing 20 which it desired to have available for the outlets 30, but the baffle system comprising the plates 44 and 45 need not and preferably should not extend inwardly into the dead space between the disks 34 but should terminate short of the central zone of the chamber 25.

Mounted on the nozzle ring 15 are a plurality of nozzles 50, preferably one juxtaposed to each of the outlet orifices 30. The nozzles 50 are inclined to the central diametric plane of the blower so that jets of liquid issuing from them are caught and carried by the jets of air issuing from the orifices 30. The ring 15 may be a split ring, of which one half serves the orifices 30 on one side of the blower and one half serves the orifices 30 on the other side of the blower. In that case, the two half rings may be served by individual pumps 13. The nozzles 50 are preferably individually valved, and the valve plates 28 of the orifices 30 corresponding to nozzles 50 temporarily not in use may be turned to close their respective orifices 30, thus adding to the force of the air issuing from the orifice which are left open.

In the operation of the blower, air will be drawn into the chamber 25 by the impellers 32 and 33 in opposed annular blasts, a relatively dead air space being formed between the disks 34. Even though the air will naturally turn to seek the outlets 30, if the air blasts were permitted to meet head-on throughout their annular extent, there would be great turbulence within the chamber 25, and the force at the various outlets 30 would fluctuate. By giving direction to a relatively small portion of the total air by means of the plates 44 and 45, a directional pattern for all of the air is established in which turbulence at the center of the chamber 25 is changed to a relatively steady flow towards the outlets. This flow assists the flow of the major portion of the air in taking short direct paths to the outlets, and the force at the outlets is made relatively constant.

I claim:

1. In a machine for spraying liquids by means of car-

rier air blasts: a casing having two opposed end walls spaced to define a single chamber between them, said walls being inclined toward one another throughout a portion of their outer margins to provide a restricted passage from said chamber, said casing having outlet orifices within said restricted passage, and having a closure wall connecting said end walls so as to close egress from said chamber except through said outlet orifices, each of said end walls having annular opposed inlet orifices; a pair of impellers rotatably mounted within said chamber and arranged to impel air from said inlet orifices toward the central plane of said chamber in opposed blasts; a baffle within said chamber extending inwardly from said closure wall generally parallel to and equidistant from said end walls, said baffle intervening between segments of said inlet orifices adjacent said closure wall and arranged to deflect that portion of the air blasts entering said chamber through inlet orifices adjacent said closure wall across said chamber substantially at right angles to and into the remaining portion of the air blasts and toward said outlet orifices, whereby all of the air entering said chamber is pneumatically guided towards said outlet orifices and is compressed between said convergent portions of said end walls; and a nozzle ring outside of said casing having a plurality of nozzles arranged to inject liquid into air jets issuing from said outlet orifices in jets convergent with the air jets.

2. In a machine for spraying liquids by carrier air blasts, a casing having two opposed end walls and a side wall enclosing a chamber, said side wall having outlet orifices in a portion of its periphery, and having a closed portion; means for introducing liquid into air issuing from said orifices; impellers respective to each of said end walls and rotatable in parallel planes so as to blow opposed air blasts toward the central plane of said chamber, said end walls having air inlets admitting to said impellers, and a baffle system extending inwardly between said impellers from the closed portion of said side wall so as to intervene between air blasts generated in opposed segments of the fields of rotation of said impellers adjacent to said closed portion and to deflect the so-baffled air towards the central portion of said chamber said baffle system comprising a first plate disposed in a plane parallel to said impellers and at least one plate disposed in a plane at right angles to said first plate and extending on both sides of said first plate, said plates terminating short of said central portion.

3. In a machine for spraying liquids, the construction set forth in claim 2, and means shielding the central portions of said impellers so as to prevent the direct entry of air into the center of said casing between said impellers, said air inlets being radially beyond said shielding means.

4. In a blower: a casing defining a short generally cylindrical single chamber and having parallel end walls, said end walls having annularly arranged inlet orifices admitting to said single chamber; two fans mounted rotatably within said casing in spaced opposed operative relationship and having their blade ends in annular juxtaposition to said inlet orifices; said casing having a circumferential wall having radial air outlets between said fans in a major circumferential portion of said wall and having a closed-minor circumferential portion; and baffles disposed between said fans on that one side of the axis of rotation of said fans adjacent said closed wall portion so as to deflect opposed air blasts across the space within said casing centrally disposed with respect to said inlet orifices toward said outlet orifices, said baffles then terminating so as to permit said deflected air blasts to become a unified stream within said casing.
